(57) **CLAIM**

The ornamental design for a carrying case for portable phone and pager, as shown and described.

DESCRIPTION

FIG. 1 is a front elevational view of the carrying case for portable phone and pager of the present invention;

FIG. 2 is a rear elevational view of the carrying case for portable phone and pager of FIG. 1;

FIG. 3 is a left side elevational view of the carrying case for portable phone and pager of FIG. 1;

FIG. 4 is a right side elevational view of the carrying case for portable phone and pager of FIG. 1;

FIG. 5 is a top plan view of the carrying case for portable phone and pager of FIG. 1; and,

FIG. 6 is a bottom plan view of the carrying case for portable phone and pager of FIG. 1.

The break lines shown in FIGS. 1-4 indicate indeterminate length.

The broken lines shown on the case indicate top stitching.
